PIPERAZINE DERIVATIVES AND PROCESS OF PREPARING

Armiger H. Sommers, Lake Forest, Ill., assignor to Abbott Laboratories, North Chicago, Ill., a corporation of Illinois

No Drawing. Application December 31, 1958
Serial No. 784,096

10 Claims. (Cl. 260—268)

This application relates generally to a new series of piperazine compounds and more specifically to a new series of N-(o-alkoxyphenyl)-N'-alkoxyalkyl piperazines and to a novel means of preparing said compounds.

In the treatment of hypertensive states, therapy usually requires the administration of a drug over a prolonged period, and it is essential that the drug have a good therapeutic ratio with no serious untoward effects. It is particularly desirable that a drug be substantially non-toxic, effective orally, and able to produce a significant reduction in blood pressure. It is also highly desirable that the patient's blood pressure be lowered an amount which is proportional to the dosage of the drug administered and that the recumbent blood pressure of the patient as well as the blood pressure of the patient when standing be lowered by the drug.

The compounds of the present invention which have been found to satisfy the foregoing requirements and which have a therapeutic activity when administered in the range of 25 mg. oral dose for an average man, preferably every four hours or at greater intervals if administered in a prolonged release dosage form and according to a doctor's prescription, have the following general formula:

wherein R is a lower alkyl group having from 1 to 6 carbon atoms, R' is an alkyl group having from 1 to 12 carbon atoms, and n is an integer from 2 to 12 inclusive.

Compounds having the foregoing general formula can be prepared in the following manner:

(1) By reacting an N,N-bis-(β -haloethyl)-arylamine with the appropriate alkoxyalkylamine, preferably in an inert organic solvent, such as 95% ethanol, in accordance with the following general equation:

wherein R, R' and n have the above-specified values, and X is Cl, Br, or I. Two additional moles of the amine or other equivalent base may be used in the reaction to accept the two moles of the hydrohalic acid formed.

(2) By the reaction of an N-(o-alkoxyphenyl)-piperazine with the appropriate alkoxyalkyl halide according to the following general equation:

wherein R, R', n and X have the above-specified values.

2

(3) By the reaction in a suitable solvent of an N-(o-alkoxyphenyl)-piperazine with the p-toluenesulfonic acid ester of the appropriate alkoxy carbinol according to the following general equation:

wherein R, R' and n have the above-specified values. Other aryl sulfonic acid esters may be used instead of the p-toluenesulfonic acid ester, such as benzene sulfonic acid esters.

The following specific examples are for the purpose of illustrating the present invention and should not be construed to limit the invention to the specific proportions and compounds used and prepared.

EXAMPLE I

N-(o-methoxyphenyl)-N'-(3-methoxypropyl)-piperazine

A flask is charged with a mixture of 124 g. (0.5 mole) of N,N-bis-(β -chloroethyl)-o-anisidine, 134 g. (1.5 moles) of 3-methoxypropylamine, and 550 ml. of 95% ethanol. The mixture is heated at reflux for about three hours or until reaction is complete and then is concentrated on a steam bath to remove most of the solvent. The residue is treated with 500 ml. of water and 200 ml. of benzene and shaken well. The aqueous layer is separated and again shaken with 200 ml. of benzene. The combined benzene solutions are shaken once with 100 ml. of water, separated, and concentrated. Distillation of the residual oil gives 116 g. of product, N-(o-methoxyphenyl)-N'-(3-methoxypropyl)-piperazine, a colorless oil boiling at about 138° C. at 0.1 mm. pressure and $n_D^{25}=1.5369$. Chemical analysis calculated for $C_{15}H_{24}N_2O_2$: Theory 68.14% C; 9.15% H and 10.60% N; as compared with the found analysis of 68.35% C; 9.43% H and 10.63% N.

Following the same procedure used in Example 1, it is possible to obtain the said product by using a mole to mole ratio of N,N-bis-(β -chloroethyl)-o-anisidine and 3-methoxypropylamine together with one mole of sodium carbonate which neutralizes the hydrogen chloride formed in the reaction. Similarly, two moles of triethylamine can be used instead of the sodium carbonate as the acid acceptor.

Several salts of the above base products can be prepared by treating a solution of the said base in ethanol with an ethanolic solution of the appropriate acid in suitable molar amounts, cooling the reaction solution, filtering the precipitated salt and drying. Thus, the mono hydrochloride salt of the said base was found to melt at 155–158° C. and the dihydrochloride salt was found to have a M.P. of 205–206° C. The furmarate salt of the said base was found to have a M.P. of 143° C. and the phosphate salt of the said base was found to have a M.P. of 143–144° C.

EXAMPLE II

N-(o-methoxyphenyl)-N'-(3-methoxypropyl)-piperazine

A mixture of 8.2 g. (0.0425 mole) of N-(o-methoxyphenyl)-piperazine, 6.5 g. (0.0425 mole) of 3-bromo-propyl methyl ether, and 4.3 g. (0.0425 mole) of triethylamine is placed in a 100 ml. 3-necked flask along with 50 ml. of xylene. The mixture is heated for six

hours at reflux, then cooled, extracted with three 30 ml. portions of 3N HCl. The acid solution is extracted with three 50 ml. portions of benzene, and is then saturated with potassium carbonate and extracted again with three 50 ml. portions of benzene. The benzene extracts are washed free of base with water, and distilled to remove solvent. The residue is distilled under vacuum to give the product boiling at 135-137° C. at 0.15 mm. pressure.

EXAMPLE III

N-(o-methoxyphenyl)-N'-(3-methoxypropyl)-piperazine

To 39 g. of *N*-(o-methoxyphenyl)-piperazine is slowly added, with stirring, 25 g. of 3-methoxypropyl-p-toluene-sulfonate. The mixture is heated for two hours on the steam bath and is then cooled and treated with 200 ml. of 10% aqueous sodium hydroxide solution. The mixture is extracted with 200 ml. of benzene and the organic extract is separated and fractionally distilled to obtain the product, *N*-(o-methoxyphenyl)-*N'*-(3-methoxypropyl)-piperazine.

EXAMPLE IV

*N-(o-ethoxyphenyl)-N'-(3-methoxypropyl)-piperazine*A mixture of 13.1 g. of *N,N*-bis-(β -chloroethyl)-o-ethoxyaniline, 13.4 g. of 3-methoxypropylamine and 75 ml. of 95% ethanol is heated at reflux for 12 hours. After evaporation of the solvent, 250 ml. of water is added to the residue which is then shaken with 100 ml. and 50 ml. portions of benzene. The combined organic extracts are shaken with 100 ml. of water, separated and distilled. This gives 11.6 g. of product, *N*-(o-ethoxyphenyl)-*N'*-(3-methoxypropyl)-piperazine, a colorless oil which boils at 131-135° C. at 0.1 mm. pressure, and $n_D^{25}=1.5270$. Analysis calculated for $C_{16}H_{26}N_2O_2$: Theory 69.03% C; 9.41% H and 10.06% N; as compared with the found analysis of 69.04% C; 9.50% H and 10.14% N.

By dissolving the above base in isopropyl alcohol and adding two equivalents of hydrogen chloride per mole of the base, one obtains the dihydrochloride salt thereof as white crystals having a M.P. of 170° C. Analysis calculated for $C_{16}H_{28}Cl_2N_2O_2$: Theory 7.97% N, as compared with the found analysis of 7.87% N.

EXAMPLE V

N-(o-methoxyphenyl)-N'-(2-methoxyethyl)-piperazine

A solution of 25 g. of *N,N*-bis-(β -chloroethyl)-o-anisidine and 23 g. of 2-methoxyethylamine in 100 ml. of 95% ethanol is heated at reflux for six hours. The solvent is evaporated on a steam bath and the residue is treated with 200 ml. of water. The mixture is shaken with 150 ml. of benzene, and the benzene extract is distilled to give the product, *N*-(o-methoxyphenyl)-*N'*-(2-methoxyethyl)-piperazine having a B.P. of 134° C. at 0.1 mm. pressure and $n_D^{25}=1.5423$. Chemical analysis calculated for $C_{14}H_{22}N_2O_2$: Theory 67.16% C; 8.86% H; 11.19% N and 12.78% O; as compared with the found analysis of 67.08% C; 8.86% H; 11.13% N and 13.01% O. The phosphate salt of the above base has a M.P. of 158-159° C.

EXAMPLE VI

N-(o-methoxyphenyl)-N'-(3-isopropoxypropyl)-piperazine

A solution of 25 g. of *N,N*-bis-(β -chloroethyl)-o-anisidine and 35 g. of 3-isopropoxypropylamine in 100 ml. of 95% ethanol is heated at reflux for three hours. The solvent is removed on a steam bath and the residue is treated with 250 ml. of water. The mixture is shaken with 150 ml. of benzene and the benzene extract is separated and distilled to obtain the product,

N-(o-methoxyphenyl)-*N'*-(3-isopropoxypropyl)-piperazine, having a B.P. of 153-155° C. at 0.2 mm. pressure and $n_D^{25}=1.5245$. Chemical analysis calculated for $C_{17}H_{28}N_2O_2$: Theory 69.82% C; 9.65% H; 9.58% and 10.94% O; as compared with the found analysis of 69.93% C; 9.80% H; 9.63% N and 11.25% O. The dihydrochloride salt of the above base has a M.P. of 175-180° C.

EXAMPLE VII

N-(o-methoxyphenyl)-N'-(3-ethoxypropyl)-piperazine

A solution of 25 g. of *N,N*-bis-(β -chloroethyl)-o-anisidine and 31 g. of 3-ethoxypropylamine in 75 ml. of 95% ethanol is heated at reflux for three hours. The alcohol is removed by evaporation on a steam bath and the residue is treated with 200 ml. of water. The mixture is shaken with 150 ml. of benzene and the benzene extract is separated and distilled to obtain the product, *N*-(o-methoxyphenyl)-*N'*-(3-ethoxypropyl)-piperazine, having a B.P. of 139-141° C. at a pressure of 0.1 mm. and a refractive index of $n_D^{25}=1.5294$. Chemical analysis calculated for $C_{16}H_{26}N_2O_2$: Theory 69.03% C; 9.41% H; 10.06% N; as compared with the found analysis of 69.05% C; 9.33% H and 9.44% N. The dihydrochloride salt of the above base has a M.P. of 174-175° C.

EXAMPLE VIII

*N-(o-methoxyphenyl)-N'-(4-methoxy-n-butyl)-piperazine*A solution of 25 g. (0.1 mole) of *N,N*-bis-(2-chloroethyl)-o-anisidine and 31 g. (0.3 mole) of 4-methoxybutylamine in 100 cc. of 95% ethanol is heated at reflux for three hours and is then concentrated on a steam bath under vacuum. To the residue is added 150 ml. of water, and the mixture is shaken with 150 ml. and 100 ml. portions of benzene. The combined benzene extracts are concentrated and distilled giving 24 g. of product, a light oil which boils at 136-140° at 0.1 mm., $n_D^{25}=1.5318$. Analysis: Calculated for $C_{16}H_{26}N_2O_2$: C, 69.0%; H, 9.41%; N, 10.1%; O, 11.5%. Found: C, 69.0%; H, 9.39%; N, 10.2%; O, 11.4%.

The product reacts with picric acid in alcohol solvent to form a dipicrate salt, M.P. 158-159°. Analysis: Calculated for $C_{28}H_{32}N_8O_16$: N, 15.2%. Found: N, 15.2%.

EXAMPLE IX

50 *N*-(o-methoxyphenyl)-*N'*-(3-methoxybutyl)-piperazine (and dihydrochloride salt)A mixture of 11.5 g. (0.06 mole) of 1-(o-methoxyphenyl)-piperazine and 7.5 g. (0.03 mole) of 3-methoxybutyl-p-toluene sulfonate is heated with steam for 14 hours. The resulting oil is taken up in 300 cc. of water and the mixture is shaken with three 75 cc. portions of benzene. Distillation gives 6.5 g. (78%) of product boiling at 140° at 0.3 mm., $n_D^{25}=1.5317$. Analysis: Calculated for $C_{16}H_{26}N_2O_2$: C, 69.0%; H, 9.4%; N, 10.1%. Found: C, 69.1%; H, 9.6%; N, 10.2%.

The dihydrochloride salt prepared in isopropanol melts at 160-162°. Analysis: Calculated for $C_{16}H_{28}Cl_2N_2O_2$: C, 54.7%; H, 8.0%. Found: C, 54.8%; H, 8.3%.

EXAMPLE X

70 *N*-(o-methoxyphenyl)-*N'*-(5-methoxypentyl)-piperazineA solution of 6.4 g. of *N,N*-bis-(2-chloroethyl)-o-

anisidine and 9 g. of 5-methoxypentylamine in 75 ml. of 95% ethanol is heated at reflux overnight. It is then concentrated and the residue is treated with 100 ml. of water. The mixture is shaken with 100 ml. and 50 ml. portions of benzene and the combined benzene extract is concentrated and distilled. There is obtained 5 g. of product, a light oil boiling at 146-149° at 0.1 mm., $n_{D}^{25}=1.5287$. Analysis: Calculated for $C_{17}H_{29}N_2O_2$: C, 69.8%; H, 9.65%; N, 9.58%. Found: C, 69.5%; H, 9.37%; N, 9.58%.

The product reacts with alcoholic picric acid to yield a dipicrate salt, M.P. 149-150°. Analysis: Calculated for $C_{29}H_{34}N_8O_{18}$: N, 14.9%. Found: N, 14.8%.

EXAMPLE XI

N-(*o*-methoxyphenyl)-*N'*-(6-methoxyhexyl)-piperazine

A solution of 8.2 g. of *N,N*-bis-(β -chloroethyl)-*o*-anisidine and 13.1 g. of 6-methoxyhexylamine in 75 cc. of 95% ethanol is heated at reflux for four hours and is then concentrated. To the semi-solid residue is added 150 ml. of water and 100 ml. of benzene and the mixture is shaken well. The organic layer is separated and distilled. There is obtained 8 g. of product, a light oil which boils at 155-160° at 0.1 mm., $n_{D}^{25}=1.5252$. Analysis: Calculated for $C_{18}H_{30}N_2O_2$: C, 70.6%; H, 9.87%; N, 9.14%. Found: C, 70.3%; H, 9.64%; N, 9.10%.

The base reacts in isopropyl alcohol with hydrogen chloride to yield a dihydrochloride salt, M.P. 172-176°. Analysis: Calculated for $C_{18}H_{32}Cl_2N_2O_2$: C, 57.0%; H, 8.50%; N, 7.38%. Found: C, 56.7%; H, 8.06%; N, 7.38%.

EXAMPLE XII

N-(*o*-methoxyphenyl)-*N'*-(7-methoxyheptyl)-piperazine

A solution of 7.5 g. of *N,N*-bis-(2-chloroethyl)-*o*-anisidine and 13 g. of 7-methoxyheptylamine in 100 ml. of 95% ethanol is heated at reflux for 17 hours and then concentrated to an oil which is treated with 100 ml. of water. The mixture is shaken with 100 ml. of benzene and the benzene layer is concentrated and distilled yielding 6.6 g. of product, an oil boiling at 157-160° at 0.2 mm., $n_{D}^{25}=1.5219$. Analysis: calculated for $C_{19}H_{32}N_2O_2$: C, 71.2%; H, 10.1%; N, 8.74%. Found: C, 71.4%; H, 10.2%; N, 8.76%.

The product reacts in alcoholic solution with anhydrous hydrogen chloride to form a dihydrochloride salt which melts at 178°. Analysis: Calculated for $C_{19}H_{34}Cl_2N_2O_2$: C, 58.0%; H, 8.71%; N, 7.12%. Found: C, 58.2%; H, 8.61%; N, 7.12%.

(a) 7-METHOXYHEPTYLAMINE

A mixture of 15 g. of 6-methoxyenanthonitrile, 15 ml. of liquid ammonia, 7 g. of Raney nickel catalyst and 500 cc. of methanol is shaken at 100° under 1500 lb. per square inch pressure of hydrogen for 20 minutes, when hydrogenation is complete. The mixture is filtered and distilled to obtain 13 g. of product, B.P. 106°/25 mm., $n_{D}^{25}=1.4338$. Analysis: Calculated for $C_8H_{19}NO$: C, 66.2%; H, 13.2%; N, 9.64%. Found: C, 66.1%; H, 13.1%; N, 9.79%.

Other higher alkoxyalkyl derivatives of *o*-alkoxyphenyl piperazines coming within the scope of the present invention can be made by any of the foregoing methods. Thus *N*-(*o*-methoxyphenyl)-*N'*-(11-methoxyundecyl)-piperazine, for example, is prepared by refluxing for about 12 hours a mixture of 11-bromoundecylmethylether (0.1 mole) and *N*-(*o*-methoxyphenyl)-piperazine (0.1 mole) with an inert solvent, such as xylene, which con-

tains triethylamine as an acid acceptor in accordance with the procedure of Example 11 described herein. In the same manner, *N*-(*o*-methoxyphenyl)-*N'*-(8-methoxyoctyl)-piperazine is prepared by refluxing a mixture of 8-bromoocetylmethylether (0.1 mole) and *N*-(*o*-methoxyphenyl)-piperazine (0.1 mole) as in Example 11 and *N*-(*o*-methoxyphenyl)-*N'*-(9-methoxynonyl)-piperazine is prepared by refluxing a mixture of 9-bromononylmethylether (0.1 mole) and *N*-(*o*-methoxyphenyl)-piperazine (0.1 mole) as in Example 11.

EXAMPLE XIII

N-(*o*-methoxyphenyl)-*N'*-(3-n-hexyloxypropyl)-piperazine

A mixture of 12 g. (0.05 mole) of *N,N*-bis-(β -chloroethyl)-*o*-anisidine, 25 g. (0.15 mole) of 3-n-hexyloxypropylamine, and 50 ml. of 95% ethanol is refluxed for about 12 hours on a steam bath. The reaction mixture is then cooled, diluted with 75 ml. of water, and extracted first with 50 ml. of benzene and then with four 25-30 ml. portions of benzene. The combined benzene fractions are heated to remove the benzene and the residue is subjected to a vacuum distillation. A yield of 11.3 g. of the product *N*-(*o*-methoxyphenyl)-*N'*-(3-n-hexyloxypropyl)-piperazine is obtained having a boiling point of 185° C. at a pressure of 0.6 mm. of mercury and a refractive index of $n_{D}^{25}=1.5153$. Chemical analysis of the said product shows 71.22% C; 10.59% H; 9.28% O and 8.32% N; as compared with a theoretical analysis of 71.81% C; 10.25% H; 9.57% O and 8.38% N.

EXAMPLE XIV

N-(*o*-methoxyphenyl)-*N'*-(3-n-dodecyloxypropyl)-piperazine

A mixture of 7 g. (0.028 mole) of *N,N*-bis-(β -chloroethyl)-*o*-anisidine, 21 g. (0.086 mole) of 3-dodecyloxypropylamine and 50 ml. of 95% ethanol is refluxed for about 12 hours on a steam bath. The reaction mixture is then cooled, diluted with 75 ml. of water, and extracted first with 50 ml. of benzene and then with four 25 ml. portions of benzene. The combined benzene fractions are heated to remove the benzene and the residue is subjected to a vacuum distillation. The product, *N*-(*o*-methoxyphenyl)-*N'*-(3-n-dodecyloxypropyl)-piperazine has a boiling point of 232-234° C. at a pressure of 0.5 mm. mercury and a refractive index of $n_{D}^{25}=1.5030$. The crude picrate salt of the said product has a melting point of 127-129° C. and after recrystallization from methanol has a M.P. of 131-131.5° C. Chemical analysis of the said picrate salt shows 52.22% C; 6.15% H; 29.23% O and 12.66% N; compared with a theoretical analysis of 52.05% C; 5.98% H; 29.20% O and 12.78% N.

EXAMPLE XV

N,N-bis-(β -hydroxyethyl)-*o*-anisidine

A mixture of 49 g. of *o*-anisidine and 36 g. of ethylene oxide is heated in a closed vessel for 19 hours at a temperature of 90°. The resulting oil is distilled to obtain 69 g. of product, boiling at 145-147° C. at 0.3 mm. pressure and $n_{D}^{24}=1.5500$. Chemical analysis calculated for $C_{11}H_{17}NO_3$: Theory 62.53% C; 8.11% H; as compared with the found analysis of 62.40% C and 8.58% H.

7
EXAMPLE XVI*N,N-bis-(β -chloroethyl)-o-anisidine*To 31 g. of phosphorus oxychloride is added in portions, with shaking, 21 g. of *N,N-bis-(β -hydroxyethyl)-o-anisidine*. The mixture is then heated on a steam bath for one hour and diluted with 200 cc. of water and allow to stand for three hours to complete the reaction. The resulting solution is shaken with two 100 cc. portions of benzene. The combined benzene extracts are distilled to give 16 g. of product which boils at 146–150° C. at 1 mm. pressure and, $n_D^{25}=1.5477$. Analysis calculated for $C_{11}H_{15}Cl_2NO$: Theory 53.24% C and 6.09% H; as compared with the found analysis of 53.48% C and 5.88% H.

EXAMPLE XVII

*N,N-bis-(β -hydroxyethyl)-o-ethoxyaniline*The intermediate product, *N,N-bis-(β -hydroxyethyl)-o-ethoxyaniline* is prepared by heating together at 125° in a stainless steel bomb, 100 g. of o-phenetidine and 6.6 g. of ethylene oxide for 18 hours. The reaction mixture is distilled to yields of 1.54 g. of the said product which has a B.P. of 170–175° C. at 1 mm. pressure and $n_D^{25}=1.5387$. Analysis calculated for $C_{12}H_{19}NO_3$: Theory 6.22% N; as compared with the found analysis of 6.12% N.

EXAMPLE XVIII

*N,N-bis-(β -chloroethyl)-o-ethoxyaniline*The intermediate, *N,N-bis-(β -chloroethyl)-o-ethoxyaniline*, is prepared by adding 154 g. of *N,N-bis-(β -hydroxyethyl)-o-ethoxyaniline* to 216 g. of phosphorus oxychloride during a period of one hour, and heating the mixture on a steam bath for one additional hour. To the mixture is added 1.5 liters of water in one portion. After the exothermic reaction is completed, shake the mixture with 400 ml. of benzene, separate the benzene layer and distill to obtain 125 g. of the intermediate which has a B.P. of 141° C. at 0.4 mm. pressure and a refractive index of $n_D^{25}=1.5381$.

EXAMPLE XIX

*N-(o-methoxyphenyl)-N'-methylpiperazine*A mixture of 17.3 parts by weight of *N,N-bis-(β -chloroethyl)-o-anisidine* and 29 parts of 30% aqueous methylamine in 50 parts ethanol is heated in a closed vessel at 125° C. for eight hours. The alcohol is then removed by distillation and 150 parts of water is added to the residue which is made strongly alkaline with 25 parts of sodium hydroxide. The mixture is then shaken with two 100 cc. portions of benzene and the combined extracts are distilled to give 11 g. of product boiling at 100–101° C. at 0.3 mm. pressure, $n_D^{27}=1.5483$. Analysis calculated for $C_{12}H_{18}N_2O$: Theory 69.86% C; 8.79% H; as compared with the found analysis of 70.07% C. and 8.80% H.

The monohydrochloride salt is prepared by dissolving the free base product in isopropanol and adding one equivalent of hydrogen chloride per mole of base. On

addition of two volumes of dry ether, *N-(o-methoxyphenyl)-N'-methylpiperazine monohydrochloride* precipitates as a white crystalline solid which is collected and dried. It melts at 200–201° C. Analysis calculated for

5 $C_{12}H_{19}ClN_2O$: Theory 59.37% C; 7.89% H; as compared with the found analysis of 59.29% C. and 7.63% H.

8

EXAMPLE XX

*3-methoxybutyl-p-toluenesulfonate*To a solution of 26 g. (0.25 mole) of 3-methoxybutanol in 200 ml. of pyridine cooled to –10° C., add 54 g. (0.28 mole) of p-toluenesulfonyl chloride. The mixture is stirred at 0° C. for 20 hours, and is then treated with 220 cc. of water, in portions. The aqueous solution is extracted with ether, and the extract is dried and distilled. This gives 7.5 g. (37%) of product, a liquid boiling at 162° at 1.5 mm., $n_D^{25}=1.4996$. Analysis: Calculated for $C_{12}H_{18}SO_4$: C, 55.8%; H, 7.0%. Found: C, 56.2%; H, 7.1%.

20 The compounds of the present invention appear to have a two-fold action in that they act peripherally to lower the vascular resistance and thus the effective vascular blood pressure and also have a marked central action which reduces the causative factors operating centrally to increase the blood pressure of the patient who suffers from hypertension. The compounds are therefore particularly suitable for treating patients with progressive hypertension and also those afflicted with hypertensive encephalopathy. Because of the vaso-dilatation effect of 25 the compounds disclosed herein, they have additional utility in the treatment of many disease associated with aging, such as coronary insufficiency, cerebral insufficiency, and arterial insufficiency, and those diseases in which acrocytosis is a component, such as Raynaud's disease, scleroderma, and the like.

30 The compounds of the present invention also produce somnolence or sedation, depending on the dose administered and the condition of the patient. The compounds, moreover, reduce excitement of the patient, thus having a tranquilizing action, and also tend to relax the skeletal muscles of the patient. When a 25 mg. dose of *N-(o-methoxyphenyl)-N'-(3-methoxylpropyl)-piperazine phosphate* is administered to an average patient on retiring, there occurs in addition to a rapid drop in blood pressure, a sound peaceful sleep from which the patient readily awakens and returns to a normal state. The foregoing piperazine phosphate salt, having a hypnotic effect of shorter duration than the barbiturates, is therefore also suited for hypertensive patients who desire to take a nap 35 during the middle of the day or otherwise relax in the middle of the stress which he experiences during the day.

40 Since the piperazine compounds of the present invention are compatible with other drugs commonly used to treat the hypertensive state, they can, if desired, be combined with these other drugs, such as the hypnotics and sedatives including the barbiturates, where a prolonged somnolence is desired, the rauwolfia alkaloids and glucosides, diuretic agents, ganglionic blocking agents 45 and with combinations of the drugs commonly employed in the treatment of hypertensive heart disease.

46 The present application is a continuation application of the inventor's co-pending application Serial No. 643,545, filed March 4, 1957, now abandoned.

50 Others may readily adapt the invention for use under various conditions of service, by employing one or more of the novel features disclosed or equivalents thereof. As at present advised with respect to the apparent scope of my invention, I desire to claim the following subject matter.

I claim:

1. A chemical compound selected from the group consisting of compounds having the general formula:

wherein R is a lower alkyl group, R' is an alkyl group having between 1 and 12 inclusive carbon atoms in the alkyl chain, and n is an integer between 2 and 12 inclusive, and the acid addition salts thereof.

2. N-(o-lower alkoxyphenyl) - N' - (o-lower alkoxyalkyl)-piperazine, wherein the alkyl group has between 2 and 11 carbon atoms in the alkyl chain.

3. N-(o-lower alkoxyphenyl) - N' - (3-lower alkoxypropyl)-piperazine. 15

4. N-(o-methoxyphenyl) - N' - (3 - methoxypropyl)-piperazine.

5. N-(o-methoxyphenyl) - N' - (3-isopropoxypropyl)-piperazine.

6. N - (o - ethoxyphenyl) - N' - (3 - methoxypropyl)-piperazine.

7. The phosphate salt of N-(o-methoxyphenyl)-N'-(3-methoxypropyl)-piperazine.

8. N-(o-methoxyphenyl) - N' - (3 - methoxybutyl)-piperazine.

9. N-(o-methoxyphenyl) - N' - (5 - methoxypentyl)-piperazine.

10. N-(o-methoxyphenyl) - N' - (7 - methoxyheptyl)-piperazine.
